CLAIM

The ornamental design for a lever-handle faucet with extendable spigot, as shown and described.

DESCRIPTION

FIG. 1 is a top, front, left-side perspective view of a lever-handle faucet with extendable spigot showing my new design;

FIG. 2 is a top view thereof;

FIG. 3 is a left side elevational view thereof, the right side being mirror symmetrical thereto;

FIG. 4 is a bottom view thereof;

FIG. 5 is a front view thereof; and,

FIG. 6 is a rear view thereof.
